WORK-PIECE HOLDER FOR ELECTROPLATING MACHINES

Albert H. Hannon, Springfield, Ohio

Original application July 17, 1936, Serial No. 91,170. Divided and this application February 4, 1937, Serial No. 123,945

3 Claims. (Cl. 204—11)

This invention relates to electroprocessing machines, and in particular, to work-piece holders consisting of rotatable containers in which the work-pieces are tumbled as they are carried through the various treatment baths.

One object of this invention is to provide a work-piece holder for electroprocessing machines consisting of a container with perforated walls, the bottom of which container is formed in such a manner as to impart an additional tumbling motion to the work-pieces as the container is rotated.

Another object is to provide such a container for electroprocessing machines consisting of a perforated barrel mounted upon a rotatable shaft, this barrel having a bottom portion with a special configuration, adapted to impart an additional turning and tumbling motion to the work-pieces as the barrel rotates while it is immersed in the treatment solution.

Another object is to provide a work-piece container for electroprocessing machines consisting preferably of a frusto-conical barrel with a projecting portion adapted to provide a turning effect to the work-pieces as the barrel rotates while immersed in the treatment solution.

Another object is to provide such a container as set forth in the foregoing objects, this container being of perforated metal covered with rubber extending through the perforations, on both sides of the barrel, so as to protect the barrel from the effects of the acid.

Another object is to provide such a container supported upon a rotatable member, which in turn, is mounted in a bracket adapted to be carried by the conveying apparatus of an electroprocessing machine, the rotating means for the rotatable member and the supporting means for the bracket being insulated from the barrel and its connected parts so as to provide an effective separation of the electric current from the conveying portion of the machine.

This application is a division of my copending application, Ser. No. 91,170, filed July 17, 1936.

45 In the drawings:

Figure 1 is a side elevation of the work-piece container of this invention, showing the bracket and its connections, with the conveying mechanism at one end of an electroprocessing machine.

Figure 2 is a side elevation taken at right angles to the container shown in Figure 1, with the container and its associated mechanism transverse the side portion of the machine shown in Figure 1.

Figure 3 is a central vertical section through the work-piece container, rotating means and supporting bracket of this invention.

Figure 4 is a cross section along the line 4—4 in Figure 3, showing the major parts of the container in top plan view.

Figure 5 is a bottom plan view of the container shown in Figures 3 and 4.

Figure 6 is an enlarged fragmentary view of a portion of the container wall shown in Figure 3, disclosing the manner in which the rubber covering extends through the perforations and surrounds the metal wall of the container.

In general, the work-piece holder of this invention consists of a barrel-shaped container 15 mounted on a rotatable member which is rotatably supported by a bracket. The rotatable member is rotatable in any suitable manner, such as by a worm gear, and the bracket is attached to the conveying apparatus of an electroprocessing machine. The details of the machine itself form no part of the present invention, and are disclosed in my copending application, Ser. No. 91,170, filed July 17, 1936. The bottom of the container is made with a special configuration, as brought out in Figures 3 and 5, to impart an additional tumbling effect to the contents while the container is being rotated during its immersion in the treatment solution or electrolyte.

Referring to the drawings in detail, Figure 1 shows an end portion of an electroprocessing machine, generally designated 10, the details of this machine being simplified merely to show the connecting mechanism of a typical apparatus upon which the work-piece holder may be used. For this purpose the machine 10 consists of a vertical standard 11, arranged adjacent a solution tank 12 and having bearing supports 13 for rotatably supporting a screw shaft 14. The standard 11 also supports longitudinal members 15 constituting chain guides for a sprocket chain 16 serving as a conveyor chain. The chain guides 15 form a frame upon which the operating mechanism of the machine is supported, and are connected to other standards 11 (not shown).

Mounted upon the longitudinal members 15 constituting the chain guides is a support 17, to which a bearing arm 18 is secured as by the bolts 19. This bearing arm 18 is provided with a vertically directed bearing 20 arranged to rotatably support a vertical shaft 21 upon which are mounted a bevel gear 22 and a sprocket 23, the latter carrying the sprocket chain 16. Lubrication for the bearing 20 is provided by an oil cup 24. Meshing with the bevel gear 22 is a bevel

pinion 25 mounted upon a horizontal shaft 26, rotatably supported in the bearing block 27 constituting an intermediate member between the support 17 and the arm 18. The shaft 26 is rotated by a motor and reducing gear (not shown).

Secured to one pin 28 of the sprocket chain 16 is a chain bracket 29 carrying upper rollers 30 for engagement with the outer wall of the 10 chain guides 15 (Figures 1 and 2), and lower rollers 31. The lower portion 32 of each chain guide 15 is bent to form a bevel-like rail in which the rollers 31 are adapted to travel. The upper part 33 of the chain guide 15 is bent over so as to 15 guide the sprocket chain 16, it being assisted in this guidance by the upper rollers 30. This roller construction aids in supporting the weight of the moving parts. The conveyor chain 16 pursues an orbital path around the machine in 20 response to the rotation of the shaft 21 and sprocket 23, and is suitably supported at the opposite end of the machine by an idler sprocket (not shown).

Insulatedly mounted upon the machine is a 25 cathode rail 34, contact with which is made by a slider 35 connected by the flexible members 36 to the carrier arm 37. The slider 35 consists of a bronze contact pad universally mounted upon the chain bracket 29. The carrier arm 37 is 30 pivotally mounted upon a cross shaft 38 supported in the bosses 39 (Figure 2). The cross shaft 38 is surrounded by an insulating sleeve 40 (Figure 3) adapted to insulate the carrier arm 37 from the remainder of the machine. The 35 carrier arm 37 is provided with a projecting portion 41 having a bore 42, within which a pin 43 is secured, as at 44. The pin 43 is provided with an enlarged head 45, and serves to support a bushing, preferably a bronze bushing 46, which 40 in turn is surrounded by an insulating bushing 47. Mounted on the insulating bushing 47 is a roller 48, this being additionally insulated from the carrier arm 37 by the insulating washer 49 (Figure 3). The carrier arm 37 is provided with 45 a bore or socket 50, within which is mounted a downwardly extending non-rotatable shaft 51.

Rotatably mounted upon this shaft 51, as by the anti-friction bearings 52 and 53, is a sleeve 54 with an enlarged portion 55. Surrounding the enlarged portion 55 is an insulating bushing 56, which serves to support a worm gear 57. The worm gear 57 is thereby effectively insulated from the remainder of the work holder mechanism, and operatively engages the screw shaft 55 14 for imparting rotation to the work holder. Similarly, the insulated roller 48 engages a rail 58 which is provided with undulating portions (not shown) for raising and lowering the work container over various partitions in the tank 12. 60 When the roller 48 engages such an arcuate portion, the carrier arm 37 is forced outwardly around its pivot shaft 38, causing the shaft 51, sleeve 54 and the associated elements to be raised.

Mounted upon the sleeve 54 is a spider 59 65 having radiating arms 60 terminating in bores 61. Passing through these bores 61 are the connecting rods 62, the latter being secured as by welding to the wall, generally designated 63, of the work holder container, generally designated 70 64. The connecting rods 62 are provided with threaded portions 65, carrying nuts 66 by which the container 64 is secured to the spider 59. The spider 59 is provided with an internal socket 67 for the reception of the anti-friction bearing 52 and the retaining member 68 and collar 75

69 associated therewith. Mounted upon the lower end of the shaft 51 is a holder 70 with a hole 71 for the reception of a chain-like member 72. In this manner the chain-like member 72 conducts electricity from the work carrier arm 5 37, by way of the shaft 51, to the work-pieces within the work holder container 64. The insulating bushings 56, 47 and 40, previously mentioned, prevent the escape of electricity through the portions adjacent thereto. The walls 63 of 10 the container 64 are constructed of heavy metal 73, with perforations 74, and surrounded on all sides by a rubber layer 75 (Figure 6) in such a manner as to permit the solutions to pass through the perforations without injuring the material 15 of which the barrel is constructed.

The bottom or end wall, generally designated 76, is composed of relatively tilted portions 77 and 78 (Figure 3) separated by the intervening portions 79 and 80. Thus the arrangement of 20 the bottom portions 77 and 78 at angles to one another causes the portions 79 and 80 to engage the work-pieces so as to give them an additional tumbling effect when the container 64 is rotated. This results in a screw-like motion as the barrel 25 is rotated while it is being carried through the various solutions by the conveyor chain 16.

In the operation of the device of this invention the screw shaft 14 and vertical shaft 21 are rotated, causing the chain bracket 29 to be moved 30 horizontally along the machine until the worm gear 57 meshes with the rotating screw shaft 14. When this occurs the worm gear 57 is rotated and imparts a similar rotation to the sleeve 54, the spider 59 and the container 64. Electricity 35 is conducted to the contents of the container from the cathode rail 34 by way of the slider or contact pad 35, the flexible members 36, the carrier arm 37, the shaft 51, the holder 70, and the flexible chain-like member 72. 40

The rotation of the container 64 turns the work-pieces over and over, and this effect is greatly accentuated by the action of the portions 79 and 80 between the relatively tilted bottom portions 77 and 78. In this manner the work-pieces 45 are not merely turned over and over, but are also given an end-over-end tumbling motion by the screw-like action of the portions 79 and 80 associated with the tilted bottom portions 77 and 78. This motion causes the work-pieces to be thoroughly turned so that all sides thereof are exposed to the action of the electrolyte or treating solution, thereby increasing the quality of the treatment and shortening the time necessary for treatment. The rubber coating of the container 55 effectively prevents the attack of the metal portions 73 by the solutions as the container 64 moves through the tank 12. 50

It will be understood that I desire to comprehend within my invention such modifications as 60 come within the scope of the claims and the invention.

Having thus fully described my invention, what I claim as new and desire to secure by Letters Patent, is:

1. A work-piece holder for electro-processing machines comprising a perforated basket-shaped container having side walls and a substantially circular end wall, said end wall comprising substantially semi-circular portions tilted relatively 70 to each other with the diameters of the semi-circles at an angle to each other for imparting an additional tumbling motion to the work-pieces in said container, and means for rotating said container. 75

2. In a work-piece holder for electro-processing machines, a rotatable member, a transversely extending element mounted thereon, a perforated basket-shaped container having side walls and a substantially circular end wall, and means for securing said container to said element, said container end wall comprising substantially semi-circular portions tilted relative to each other with the diameters of the semi-circles at an angle to each other and connecting projections therebetween for engaging and tumbling the work-pieces in said container, whereby to impart to the

work-pieces an increased tumbling effect over that imparted thereto by the end wall alone.

3. A work-piece holder for electro-processing machines comprising a perforated basket-shaped container having side walls and a substantially circular end wall, said end wall comprising substantially semi-circular portions tilted relatively to each other with the diameters of the semi-circles at an angle to each other and connecting projections therebetween covered with resilient material to prevent denting of the work-pieces.

ALBERT H. HANNON.
